HYDRANT MARKER

Walter J. Doody, Boston, Mass.

Application July 7, 1944, Serial No. 543,770

1 Claim. (Cl. 88—82)

1
This invention relates to a light reflecting hydrant marker.

The invention has for an object to provide a novel and improved marker provided with light reflecting elements and which is particularly adapted for attachment to a fire hydrant or the like whereby the latter may be easily located in the dark and during snowy and inclement weather.

With this general object in view, and such others as may hereinafter appear, the invention consists in the light reflecting marker as herein-after described and particularly defined in the claim at the end of this specification.

In the drawings illustrating the preferred embodiment of the invention, Fig. 1 is a front elevation of a fire hydrant embodying the present invention; Fig. 2 is an enlarged front view of the marker shown in Fig. 1; Fig. 3 is a side elevation of the same, partly in cross-section; Figs. 4 and 5 are views similar to Fig. 3 of modified forms of the present marker; and Fig. 6 is a plan view of the marker.

In general, the present invention contemplates a novel and improved light reflecting marker for outdoor use and which is particularly adapted for attachment to a fire hydrant whereby the hydrant may be easily and quickly located after dark or during a snowstorm. The present marker is preferably designed to be attached to the upper portion of the hydrant and to extend above the top thereof. Thus during a snowstorm in which the snow is of a depth such as to entirely conceal the hydrant, the present marker is clearly visible to reveal the location of the hydrant.

Referring now to the drawings, 10 represents a fire hydrant of any usual or preferred type to which the present reflecting marker or locator 12 may be attached. As herein shown, the illustrated marker 12 comprises an elongated up-standing metallic bar 14 provided with a plurality of reflector buttons 16 preferably arranged in vertical rows upon one or more sides thereof. In the illustrated marker, as shown in cross-section in Fig. 3, the reflector buttons 16 may be supported in metal sockets 18, a pair of sockets being pressed into opposite sides of a hole drilled through the bar 14. The reflector buttons may and preferably will be of the type usually employed on road signs comprising white or colored glass buttons capable of reflecting the light from the headlights of an automobile or a search or flash-light, and which are capable of shedding snow and ice so as to be visible under inclement weather conditions.

2
The majority of the standard commercial fire hydrants of which I am aware are provided with an operating nut 20 as their uppermost part by which the hydrant valve may be opened and closed. In practice, such operating nuts are usually provided with a central opening for lubricating purposes, such opening being normally closed by a screw or plug. As herein shown, the present marker 12, as illustrated in Figs. 2 10 and 3, is provided with a threaded extension 22 at its lower end by which the marker may be conveniently attached to the hydrant by removing the lubricating screw or plug and inserting the extension 22. The marker thus attached 15 serves the purpose of the lubricating screw and may be easily removed when it is desired to lubricate the moving parts of the hydrant for opening and closing the valve.

As illustrated in Fig. 4, other types of hydrants 20 include those which are provided with an up-standing threaded portion 24 extending from the main operating stem 26. In such types of hydrants the operating nut 28 is fitted over a reduced portion 30 of the stem and a hold down 25 nut, not shown, is screwed onto the threaded portion 24 to hold the operating nut in engagement with the main operating stem 26.

In order to adapt it to the above described type of hydrant, the present marker 12 may be 30 provided with a tapped hole 32 in the bottom thereof corresponding to the threaded portion 24 of said main operating stem so that in practice the marker may be attached by merely removing the hold down nut and replacing it with the marker. Thus, in addition to serving for its 35 intended purpose as a light reflecting marker it also serves as a hold down nut for the hydrant operating nut 28.

In those instances in which the operating nut 40 has neither a tapped hole for a lubricating screw or an extended threaded portion for a hold down nut, it is merely necessary to drill and tap a hole in the top of such operating nut for the attachment of a marker such as illustrated in Fig. 3.

Referring now to Fig. 5, in some instances it 45 may be desired to provide a marker of the type having an internally threaded portion 32 with an adapter 34 to permit such type of marker to be used interchangeably for attachment to either 50 type of hydrant above described. As herein shown, the adapter comprises a flange member having threaded portions 36, 38 extending from either side thereof, one portion 36 being received in the internally threaded portion 32 of the 55 marker, and the other, 38, being received in the

tapped hole in the operating nut, as clearly shown in Fig. 5.

From the above description it will be observed that the present light reflecting marker may be used with advantage in locating hydrants in the dark and also after a snowstorm in which the snow is of sufficient depth to conceal the main portion of the hydrant, the present marker extending from the top of the latter whereby the location may be quickly revealed by a search-light thus saving valuable time in an emergency. 5

While the preferred embodiment of the invention has been herein illustrated and described, it will be understood that the invention may be embodied in other forms within the scope of the 15 following claim.

Having thus described the invention, what is claimed is:

A marker for a fire hydrant of the type having an operating nut projecting above the top portion thereof, comprising an elongated upright member adapted to be attached to such an operating nut, and a plurality of light reflecting buttons mounted in said upright member, said upright member having all cross-sectional 25 dimensions smaller than the corresponding ones 20

of said operating nut whereby to permit a closed wrench of a size to fit said operating nut to pass thereover without disturbing the marker.
